UNITED STATES PATENT OFFICE.

ALFRED STEINBART, OF PITTSBURGH, PENNSYLVANIA.

REGENERATIVE FURNACE.

1,169,296.

Specification of Letters Patent. Patented Jan. 25, 1916.

Application filed November 20, 1914. Serial No. 873,159.

To all whom it may concern:

Be it known that I, ALFRED STEINBART, a citizen of the United States, and resident of Pittsburgh, in the county of Allegheny and State of Pennsylvania, have invented certain new and useful Improvements in Regenerative Furnaces, of which the following is a specification.

My invention relates to the construction and arrangement of regenerative open-hearth and heating furnaces, and more particularly relates to the construction and arrangement of the valve chamber or pit in which the air and gas reversing valves are positioned or located. Heretofore, the flow of air into and through the air valve and air regenerators of such furnaces, has always been induced by the draft of the furnace stack and the valve chamber or pit has been open to the atmosphere, the numerous cracks, holes and other openings in the floor covering the valve pit usually being sufficient to supply air for the air valves to the valve pit. The gas used in the furnaces and heated in the gas regenerators is supplied to the gas valves under pressure slightly above that of the atmosphere, and it has been found in practice that oftentimes the air supply to the air valves is insufficient.

The primary object of my invention is to provide a regenerative furnace having improved means for supplying air to the furnace air regenerators, whereby the air supply is increased without requiring expensive alterations in the construction of the air valves, flues and regenerators of existing furnaces or costly additions to the equipment of new furnace constructions.

Another object of my invention is to provide a regenerative furnace having novel means whereby the necessary volume of air is supplied at a pressure slightly above atmospheric pressure to the air valves of a regenerative furnace or series of furnaces.

Still further objects of my invention will become apparent as the invention is more fully described hereinafter and is specifically pointed out in the appended claims.

Referring now to the drawings forming part of this specification, Figure 1 is a plan showing the valve pit or chamber of a regenerative furnace as constructed and arranged in accordance with my invention. Fig. 2 is a sectional end elevation of the same, the section being taken on the line II-II of Fig. 1. Fig. 3 is a sectional side

elevation of the apparatus shown in Figs. 1 and 2, the section being taken on the line III-III of Fig. 1.

In the accompanying drawings the numeral 2 designates the heating chamber of a regenerative heating furnace having air and gas regenerators of the usual construction on each side thereof and 3 is the valve pit or chamber in which the gas valve 4 and air valve 5 are located. The gas valve 4 is connected to the gas regenerators by the usual gas flues, and to the gas producer by the gas flue 6, and the air valve 5 is connected to the air regenerators by the usual air flues in the ordinary and well known manner. In the construction shown the air and gas valves are of the usual well known butterfly reversing type, although lifting valves or other known constructions may be employed.

The valve chamber or valve pit 3 is covered with a floor 3a and has the usual side wall 7 and end walls 8. 8, one side wall 9 of the furnace regenerators forming the opposite side wall of the valve pit. In constructing furnaces in accordance with my invention care is taken to greatly reduce the size of the cracks or other openings in the floor plates, or to entirely eliminate such openings so that the valve pit 3 is made substantially air tight.

An opening 11 is provided in one wall of the valve pit, (in an end wall as shown) and this opening communicates with a walled passage or air shaft 12 having an open upper end communicating with the atmosphere. The open upper end of the shaft 12 may be covered with a grating to permit of the free entrance of air thereto.

Positioned in front of or located within the opening 11 so as to discharge therethrough is a power driven disk fan 13 which is employed to force air into the valve pit 3 at a pressure somewhat above atmospheric pressure (a pressure of about one-tenth of an inch water head generally will be found to be sufficient). The fan 13 may be driven by a suitable motor 14 directly connected thereto, or may be connected by a belt to a motor located at a distance from the fan.

In the operation of furnaces constructed in accordance with my invention, the reversing gas valves 4 and air valves 5 are manipulated in the usual known manner and the saucer valve used in regulating the supply of air from the valve pit to the air

valve is raised and lowered in the usual manner in regulating the air supply. The disk fan 13 is started in operation, which forces air under pressure into the valve pit 5 3. This fan being of sufficient size, a large volume of air is supplied to the valve pit, which will take care of leakage of air therefrom and at the same time maintain the pressure of the air in the valve pit slightly 10 above that of the atmosphere. In this way the supply of air to the air valve is materially increased in a cheap and economical manner, and the heating capacity of the furnaces is increased.

15 It is to be understood that the valve pit may be extended in front of a plurality of furnaces so that the one fan will be utilized to supply air to a series of air valves instead of to one reversing air valve, as is 20 shown in the drawing.

The advantages of my invention will be apparent to those skilled in the art. The apparatus is simple and is easily kept in repair. By its use the air supply is increased 25 without the necessity of making excessive alterations in the equipment of existing furnaces, or additions to new furnaces.

Modifications in the construction of the fan and in its location in the walls of the 30 valve pit may be made without departing from my invention, and other changes may be made within the scope of the appended claims.

I claim:

35 1. In a regenerative furnace, the combi-

nation of an air valve connected to the furnace regenerators, an inclosed valve pit in which the air valve is positioned, and means connecting with the exterior of the valve pit for supplying air under pressure to said 40 valve pit.

2. In a regenerative furnace, the combination of an air valve connected to the furnace regenerators, an inclosed valve pit in which the air valve is positioned, and a fan 45 or blower connecting with the exterior of the valve pit for supplying air under pressure to said valve pit.

3. In a regenerative furnace, the combination of a valve pit in which the furnace 50 air valves are located, and from which the air supply is drawn into said valves, and means connecting with the exterior of the valve pit for supplying air under pressure to said valve pit.

4. In a regenerative furnace, the combination of valve pit in which the furnace air valves are located and from which the air supply is drawn into said valves, an air shaft connecting the interior of the valve 60 pit with the atmosphere, and a fan or blower in said air shaft for causing the flow of air through said air shaft into said valve pit.

In testimony whereof I have hereunto set my hand.

ALFRED STEINBART.
